US00D641180S

(12) **United States Design Patent**
Kennedy et al.

(10) **Patent No.:** **US D641,180 S**
(45) **Date of Patent:** **** Jul. 12, 2011**

(54) **HIGHCHAIR**

(75) Inventors: **Brook Kennedy**, Glen Ridge, NJ (US); **Jonathan Cedar**, Brooklyn, NY (US); **Colin Kelly**, Brooklyn, NY (US); **Troy Phipps**, Brooklyn, NY (US); **Ryan Vernon**, New York, NY (US); **Nicholas Oxley**, New York, NY (US); **Eric Freitag**, New York, NY (US)

(73) Assignee: **Helen of Troy Limited (BB)**

(**) Term: **14 Years**

(21) Appl. No.: **29/316,309**

(22) Filed: **Sep. 11, 2009**

(51) **LOC (9) Cl.** **06-01**

(52) **U.S. Cl.** **D6/339**

(58) **Field of Classification Search** ..... D6/339, D6/333-335, 338, 491, 500-502; D12/129, D21/412, 419; 280/30-31; 5/94, 98.1, 99.1, 5/101, 102, 105, 655; 297/183.1-183.4, 297/184.13, 250.1, 255, 256.15, 256.16, 297/174 R, 174 CS, 170-173

(57) **CLAIM**

The ornamental design for a highchair, as shown and described.

DESCRIPTION

FIG. 1 is a perspective view of the highchair showing our new design;

FIG. 2 is a front elevational view of the highchair shown in FIG. 1;

FIG. 3 is a rear elevational view of the highchair shown in FIG. 1;

FIG. 4 is a side elevational view of the highchair shown in FIG. 1;

FIG. 5 is a side elevational view of the highchair shown in FIG. 1;

FIG. 6 is a top plan view of the highchair shown in FIG. 1; and,

FIG. 7 is a bottom plan view of the highchair shown in FIG. 1.
